UNITED STATES PATENT OFFICE.

JOHN HOCHBERGER, OF CHICAGO, ILLINOIS, ASSIGNOR TO LILLIAN J. HOCHBERGER, OF CHICAGO, ILLINOIS.

ATTACHING MEANS FOR BIBS.

1,273,859.

Specification of Letters Patent. Patented July 30, 1918.

Application filed June 8, 1917. Serial No. 173,609.

To all whom it may concern:

Be it known that I, JOHN HOCHBERGER, a citizen of the United States, residing at Chicago, in the county of Cook and State 5 of Illinois, have invented certain new and useful Improvements in Attaching Means for Bibs, of which the following is a specification.

The present invention relates broadly to 10 improvements in plumbing fittings, its primary object being to provide novel means for attaching bibs to laundry trays or tubs.

To best obtain an understanding of the 15 advantages of the invention, it may be stated that these trays which are generally of granitine or soapstone, are provided with a relatively large opening or openings through which the plumber makes connection for the bibs with the water supply pipes. In order 20 to hold the connection in its proper place, it is customary to drive a wooden wedge or block in the opening, but this is extremely unsatisfactory owing to the fact that through shrinkage or accident the wedge be- 25 comes displaced, leaving the plumbing in unsuitable condition, conducive to leaks. With such arrangements, it is not unusual, inasmuch as trays of this character are sel- 30 dom provided with overflows, when the water is allowed to fill the trays as high as the bib, for the water to leak past the bib and onto the floor.

It is to overcome these difficulties and disadvantages that I have conceived this 35 invention which consists of a coupling member provided with clamping means and a retaining element through the instrumentality of which a filler disposed about the connection with the bib in the wall of the tray is posi- 40 tively held in place.

For a full understanding of the invention, reference is made to the accompanying draw- 45 ing, in which:

Figure 1 is a longitudinal sectional view 45 through an embodiment of the invention, and showing its application;

Fig. 2 is a view in elevation of the coupling member;

Fig. 3 is a view in elevation of a slightly modified form of the coupling; and

Fig. 4 is a similar view showing a different type of pipe connection for one end of the coupling member.

Throughout the following detail description, and on the several figures of the drawing, similar parts are referred to by like reference characters.

Referring to Fig. 1, the reference character 1 designates the rear wall of a laundry tray through which the customary opening 2 is provided. At one side of this wall is disposed the conventional bib 3 having the annular flange 3', the said bib being connected to the pipe line 4 by the special means now to be described.

At 5 is denoted a coupling member, the extremities of which are preferably threaded, one to connect with the bib and the other to connect with the pipe line 4 through the union 6. Centrally the coupling is preferably enlarged and externally threaded to receive the clamping nut 7, which coacts with a large washer 8 loosely surrounding the coupling, to impart clamping action to the bib. The washer 8 is sufficiently large to 75 cover the opening 2 in the wall of the tray and in connecting up the fitting this opening is filled with putty or other plastic material which holds the connection in central position against movement and makes the 80 tray leak proof at this point.

It will readily be understood that this coupling member 5 may be made in different lengths or sizes and as shown in Fig. 3 at 9, an extension may be provided at 85 one end, or as shown in Fig. 4, the tail piece may be of tapered form to be wiped into lead pipe; hence I do not wish to be limited to the particular form of this coupling described.

Having thus described my invention, what is claimed as new is:

The combination with a laundry tray having an opening in its wall and a bib disposed therein, of attaching means for said bib 95 comprising a coupling member reduced at

either end and threaded for connection with the bib and water supply line, the relatively large central portion of said coupling member being also threaded, a plastic filler disposed in the tray opening surrounding the connection of the coupling and the bib, a washer mounted upon said coupling and

constituting a mold form for one side of the plastic material, and means on said coupling member for holding the washer in position retaining the plastic material in the opening.

In testimony whereof I affix my signature.

JOHN HOCHBERGER.
